CLAIM

The ornamental design for a “fruit cutter,” as shown and described.

DESCRIPTION

FIG. 1 is a front and top perspective view of a fruit cutter showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and

FIG. 8 is a rear and bottom perspective view thereof; and, FIG. 9 is a perspective view of FIG. 1 used with a protective cover shown in broken line thereunder.

The broken line in the figure drawing views is included to show unclaimed environment only and forms no part of the claimed design.
